UNITED STATES PATENT OFFICE

ANDREW A. KRAMER, OF KANSAS CITY, MISSOURI

DESIGN FOR A VEHICLE TANK

Application filed March 17, 1930. Serial No. 34,930. Term of patent 14 years.

To all whom it may concern:

Be it known that I, ANDREW A. KRAMER, a citizen of the United States, residing at Kansas City, in the county of Jackson and State of Missouri, have invented a new, original, and ornamental Design for Vehicle Tanks, of which the following is a specification, reference being had to the accompanying drawing, forming a part thereof.

Fig. 1 is a perspective view of the vehicle

tank showing my new design, as viewed from the front thereof.

Fig. 2 is a side elevation thereof.

Fig. 3 is a top plan view thereof and

Fig. 4 is a front elevation thereof.

I claim:

The ornamental design for a vehicle tank substantially as shown.

In testimony whereof I hereunto subscribe my name this 7th day of February, 1930.

ANDREW A. KRAMER.
